UNITED STATES PATENT OFFICE

2.529.193

SAFETY BOOM STOP

Earle F. Rueter, Milwaukee, Wis., assignor to Unit Crane & Shovel Corp., West Allis, Wis., a corporation of Delaware

Application December 26, 1945, Serial No. 637,237

(Cl. 212-39)

The present invention relates to stop apparatus and more particularly to safety boom stops for rotary cranes and the like.

In the operation of a mobile rotary crane it is necessary for safety reasons to avoid raising the pivoted hoist boom beyond a predetermined height. Boom stops for this purpose have heretofore been devised, but these have been open to various objections such as complexity of construction and relatively high cost of manufacture.

An object of the invention is to provide an improved safety boom stop which is of simple and inexpensive construction and readily applicable to existing machines.

Another object is to provide a boom stop which is reliable in operation and which will not interfere with the lowering of the boom from its stopped position. A further object is to provide a boom stop which is particularly suitable for a load-handling machine powered by an internal combustion

The invention further consists in the several features hereinafter described and claimed.

In the accompanying drawings, illustrating certain embodiments of the invention,

Fig. 1 is a schematic elevational view of a safety boom stop arranged in accordance with the invention, a switch casing thereof being shown in section; and

Fig. 2 is a fragmentary elevational view of the switch actuating mechanism as it appears when displaced by the raised boom, parts being shown in section.

Fig. 3 is a transverse sectional elevational view taken at the point indicated by the arrow in Fig. 2.

Fig. 4 is a schematic wiring diagram of the stop as applied to a crane having an engine with battery ignition.

Fig. 5 is a schematic wiring diagram of the stop as applied to a crane having an engine with magneto ignition;

Fig. 6 is an elevational view of a modified form of stop switch device, parts being shown in section:

Fig. 7 is a sectional elevational view taken generally along the line 7—7 of Fig. 6;

Fig. 8 is a schematic wiring diagram of a modified form of circuit for the boom stop, and Fig. 9 is a side elevation of a rotary crane equipped with a boom stop of the invention.

parts being shown schematically. Referring to Figs. 1 to 4 and 9, the numeral 10, Fig. 9, designates generally a mobile rotary

2
crane of any usual construction. The machine includes a propelling undercarriage 11, here shown to be of the crawler type, although a wheel-type undercarriage may be used, as is well understood in this art. A rotating frame or turntable 12 is rotatably mounted on the undercarriage and carries the usual mechanism for operating the machine, this mechanism including a gear-case 13 and an engine or motor 14. One suitable type of undercarriage and operating mechanism is shown in United States Patent 2,318,286, to Harold E. Brey and Hilbert E. Swanson, for Traction Brake, issued May 4, 1943. The engine 14 is connected to the gear-case by a friction clutch 15, Fig. 1, controlled by the usual actuating linkage 16. The gear-case includes the usual boom-hoisting drum 17 and load-hoisting drum 18, the drum 17 being rotated in any well-known manner as by a suitably controlled worm drive 19, Fig. 1. The turntable carries the usual A-frame 20, Fig. 9, and also a suitable cab 21 having a front wall 22 and side wall 23, Fig. 1.

A hoist boom 24 is pivotally connected at 25 to projecting supporting parts 26 at the front of the turntable to swing in a vertical plane, and is adjustably elevated by a hoisting cable 27 which is wound on the drum 17 and passes over sheaves 28 on the boom point and sheaves 29 on the A-frame, as usual. A load-hoisting cable 30 is wound on the drum 18 and passes over sheaves 31 on the boom point and over a sheave 32 at a suspended load-engaging hook 33, as usual.

35. In accordance with usual practice, the hoisting machine may be readily converted to various other forms, such as a clam shell, dragline, back-digger, and excavating shovel, by providing suitable booms and other equipment. A

40 machine of this type converted to an excavating shovel is disclosed in United States Patent 2,304,486, to Hilbert E. Swanson, for Crowd for Boom Structures, issued December 8, 1942.

In accordance with the present invention, stop means are provided for limiting the raising of the pivoted boom 24 beyond a predetermined height. The stop means comprises a control device designated generally by the numeral 34 and adapted to cooperate with the boom, as hereinafter described. The control device 34 includes a casing 35 adapted to be rigidly mounted on the crane cab and having front and rear walls with aligned bores 36 in which is slidably mounted a horizontal forwardly projecting rod 37 with an abutment disk 38 at its exposed front

end, the rod passing through an opening 39 in the front wall 22 of the cab. A collar 40 is secured to the rod by a pin 41 and is urged forwardly to a normal position against the front wall of the casing by a coiled spring 42 which surrounds the rod and bears against the rear wall of the casing. The casing 35 is here shown to be secured by bolts 43 to the cab side wall 23 which latter forms a closure for the casing.

A plate 44 is secured to the foot portion of the boom at a suitable distance above the pivot 25 and carries a bolt 45 which is clamped in longitudinally adjusted position by nuts 46. A roller 47 is carried on the free end of the bolt and is adapted to abut against the end disk 38 of the stop rod 37 to force this rod rearwardly when the boom is raised to its safe maximum height. Electric switches 48 and 49 are rigidly secured in the casing 35 and are respectively disposed below and above the rod 37, each switch being mounted on a spacer block 50; Fig. 3. These switches include respective pivoted plunger-actuating roller arms 51 and 52, the rollers 53 of which bear on diametrically opposite sides of the collar 40, the latter having a cylindrical surface 54 and a conical cam surface 55. The two switches, or at least the free ends of the roller arms thereof, are longitudinally offset so that the switch 48 will operate slightly in advance of the switch 49 when the cam collar is returned to the normal position of Fig. 1 by the spring 42. The switches per se are of well known construction and preferably of a snap-action type. The switch 48 is spring-urged to open position and requires the application of pressure to its roller arm to hold it in closed position. The switch 49 is of the maintained-contact or locking type and includes a reset button 56 by which the switch can be manually actuated to closed position, the application of pressure to the roller arm 52 snapping the switch to its open position. In the position of the parts shown in Figs. 1 and 4 the switch 48 is held closed and the switch 49 is open. The switches 48 and 49 are preferably of the double-throw type, permitting each to be used either as a normally open switch or a normally closed switch, the switch 48 having selectively usable contacts 48a and 48b and the switch 49 having selectively usable contacts 49a and 49b.

In the present instance, the switches 48 and 49 are connected in the ignition circuit of the crane engine, the switch 48 being a boom-actuated limit switch for stopping the engine when the boom is raised to its highest safe position. In Figs. 1 and 4, the ignition circuit is shown to be of the battery type and includes a battery 57, manual ignition switch 58, breaker 59, with shunting condenser 60, high-tension coil 61 with primary and secondary windings, and distributor 62 connected to the engine spark plugs 63, all as usual. The limit switch 48 is connected in series with the manual ignition switch 58, the connection being made to the switch contact 48a, Fig. 4. The manually operable switch 49 is connected in shunt to the switch 48, the connection being made to the switch contact 49a. In the position of the parts shown in Figs. 1 and 4, the limit switch 48 is held in closed position by the cylindrical surface 54 of the cam collar 40 so as to complete the ignition circuit and permit operation of the engine.

In the operation of the system of Figs. 1 and 4, the raising of the boom to its highest safe position will push the spring-pressed rod 37 inwardly to the position of Fig. 2, permitting the limit

switch 48 to snap to its open position, thus opening the engine ignition circuit and stopping the engine. This serves as a signal to the operator who then disconnects the driving connection to the boom-hoisting drum 17 and releases the engine clutch 15. The operator then momentarily depresses the reset button 56 of the switch 49 which locks in closed position and reestablishes the ignition circuit through the switch contact 49a, thus permitting restarting of the engine. After the engine is again in operation the boom is lowered by manipulating the usual controls, permitting the advance of the spring-pressed stop rod 37 to its normal position. During this advance, the limit switch 48 is restored to its closed position by the cam surface 55 acting on the switch arm 51, and shortly thereafter the switch 49 is restored to its open position by the cam surface 55 acting on the switch arm 52, thus placing the control device in condition for a subsequent boom-stopping operation.

Occasionally, the boom may be lifted to its highest safe position by contact with a tree branch or other obstruction while the crane is travelling. However, the control device will function as above described to stop the engine, thus immediately stopping the crane and preventing damage.

In the modified form of the invention shown in Fig. 5, the crane engine 14 is provided with a high-tension ignition magneto 61'. This form of magneto is usually rendered ineffective by short-circuiting or grounding the primary winding, as by a manual switch 58'. In applying the control device to this form of magneto circuit, the switches 48 and 49 are connected in series by way of the contacts 48b and 49b to form a shunt around the manual switch 58', the limit switch 48 being normally open but movable to closed position upon the retraction of the stop rod 37 by the boom, and the reset switch 49 being normally closed but movable to open position by the reset button 56 so as to permit restarting of the engine. Since the control switches 48 and 49 are of the double-throw type, the same switches can be used for the circuits of Figs. 4 and 5 with suitable changes in the wiring, as shown.

In the operation of the stop means when arranged as in Fig. 5, the raising of the boom to the limit position closes the switch 48, thus short-circuiting the magneto primary winding and stopping the engine. By pressing the reset button 56 of the switch 49, the magneto primary circuit is reopened, thus permitting restarting of the engine. A slight lowering of the boom then re-opens the limit switch 48 and recloses the switch 49, thereby placing the control device in condition for a subsequent boom-stopping operation.

In the modified form of control device shown in Figs. 6 and 7, the stop rod 37 is slidable in a casing 35' and the switches 48 and 49 are mounted in the casing side-by-side above the stop rod 37. A cam collar 40' is secured on the rod as by a pin 41 and is urged forwardly by a coiled spring 42, as in the device of Fig. 1. The roller arms 51 and 52 of the switches cooperate with a flat horizontal surface 54' and a flat sloping cam surface 55' formed on the cam collar. The casing 35' can be somewhat smaller than the casing 35, but it is necessary to prevent turning of the cam collar 40' which can be done in any suitable manner, as by means of a stationary key 64 secured in the casing and engaging in a side channel 65 in the cam collar. The construction

and operation of the device of Figs. 6 and 7 is otherwise the same as that of Fig. 1.

In the modified form of the invention shown in Fig. 8, the reset switch 49 is connected in series with an interlock switch 66 which is opened by a boom hoist control lever 67 when the latter is in hoisting position, thus preventing restarting of the engine until this control lever is moved out of hoisting position. The limit switch 48 is connected in a control circuit including the switch contact 48a, a battery 68, and the winding 69 of a relay switch 70, the circuit also including a manual switch 71. The relay switch controls a suitable engine-enabling circuit here shown to include the battery 68, the relay switch contacts, a winding 72 of an engine stop 73, and the manual control switch 71. By way of example, the engine-enabling circuit may be an ignition circuit similar to that of Fig. 4 or Fig. 5.

In the case of a compression-ignition engine, the circuit may control the engine emergency stop, one known type of which functions by shutting off the air supply. The stop is also applicable to control a crane of the electric motor-driven type.

The system of Fig. 8 further includes an alarm circuit having therein one or more alarm devices, such as a bell 74 and a lamp 75, these alarm devices being supplied with current by the battery 68, and the alarm circuit being established through the contact 48b of the limit switch 48.

In the operation of the system of Fig. 8, the raising of the boom to its highest safe position actuates the limit switch 48, opening the control circuit through the relay winding 69 and closing the alarm circuit. The relay switch thereupon opens the engine stop circuit including the winding 72, causing stopping of the engine or motor. After shifting the boom hoist control lever 67 out of hoisting position, the operator depresses the reset button 56 of the switch 49 to effect closing of this switch, thereby reestablishing the relay control circuit through the then closed series-connected switches 49 and 66. The relay switch 70 then closes, permitting restarting of the engine. Since the boom hoist control lever is then out of hoisting position, there is no danger of continued raising of the boom. As the boom is lowered the limit switch 48 is returned to normal position, thus opening the alarm circuit and establishing a path for the current flowing through the relay switch winding 69. Shortly thereafter the reset switch 49 opens, placing the device in condition for a subsequent boom-stopping operation.

What I claim as new and desire to secure by Letters Patent is:

1. In a load-handling machine having a hoist boom and power means for operating said boom including control circuit means and a boom-hoist control member movable into and out of boom-hoisting position, a limit switch connected to said circuit means and having a power-enabling position and a power-disabling position, said limit switch being normally in power-enabling position, mechanical means controlled by the boom for operating said limit switch to power-disabling position upon the raising of the boom to a predetermined height and for restoring said limit switch to power-enabling position upon the lowering of the boom from its limit position, a manually operable locking-type reset switch connected with said circuit means and having an inactive position and a power-enabling position, said reset switch being normally in inactive position and being manually operated to

power-enabling position when said limit switch is in power-disabling position, mechanical means controlled by the boom for restoring said manually operable reset switch from its power-enabling position to its inactive position upon the lowering of the boom from its limit position, and a third switch connected in circuit with said manually operable reset switch and having a mechanical actuating connection with said boom-hoist control member for rendering said reset switch ineffective to energize the power means while said control member is in boom-hoisting position.

2. In a safety stop device for a movable power operated member of a machine having power means for operating said member and electric circuit means for controlling said power means, a reciprocable member movable between a normal position and a stopping position, yieldable means for normally urging said reciprocable member toward normal position, said reciprocable member adapted to be mechanically moved in the opposite direction to stopping position by the movable member at an end of the travel of said movable member, a limit switch adapted for connection with said circuit means and having a power-enabling position and a power-disabling position, said limit switch being normally in power-enabling position, mechanical means controlled by said reciprocable member for operating said limit switch to power-disabling position upon the travel of said reciprocable member in stopping direction, a manually operable locking-type reset switch adapted for connection with said circuit means and having an inactive position and a power-enabling position, said reset switch being normally in inactive position and being manually operable to power-enabling position when said limit switch is in power-disabling position, and mechanical means controlled by said reciprocable member for restoring said reset switch to its normal inactive position upon the return travel of said reciprocable member to its normal position.

3. In a safety stop device for a movable member of a machine having power means for operating said member and electric circuit means for controlling said power means, a limit switch adapted for connection with said circuit means and having a power-enabling position and a power-disabling position, said limit switch being normally in power-enabling position, mechanical means controlled by said movable member for operating said limit switch to power-disabling position upon the movement of said movable member to a limit position and for restoring said limit switch to power-enabling position upon the movement of said movable member from its limit position, a manually operable locking-type reset switch adapted for connection with said circuit means and having an inactive position and a power-enabling position and being manually operable to power-enabling position when said limit switch is in power-disabling position, and mechanical means controlled by said movable member in its movement from limit position for restoring said reset switch from its power-enabling position to its inactive position.

4. In a safety stop device for a movable power-operated member of a machine having power means for operating said member and electric circuit means for controlling said power means, a reciprocable cam member movable between a normal position and a stopping position, yield-

able means for normally urging said reciprocable cam member toward normal position, said cam member adapted to be mechanically actuated by said movable member for moving said reciprocable member in the opposite direction to stopping position at an end of the travel of said movable member, a limit switch adapted for connection with said circuit means and having a power-enabling position and a power-disabling position, said limit switch being normally in power-enabling position, mechanical means controlled by said cam member for operating said limit switch to power-disabling position upon the travel of said cam member in stopping direction, a manually operable locking-type reset switch adapted for connection with said circuit means and having an inactive position and a power-enabling position, said reset switch being normally in inactive position and being manually operated to power-enabling position when said limit switch is in power-disabling position, and mechanical means controlled by said cam member for restoring said reset switch to its normal inactive position upon the return travel of said cam member to its normal position.

5. In a safety stop device for a movable power-operated member of a machine having power means for operating said member and electric circuit means for controlling said power means, a casing, a rod reciprocably mounted in said casing and having a cam, said rod being longitudinally movable between a normal position and a stopping position, yieldable means in said casing for normally urging said rod toward normal position, said rod projecting from said casing and adapted to be longitudinally displaced in the opposite direction to stopping position by said mov-

able member when said movable member approaches an end of its travel, a limit switch in said casing adapted for connection with said circuit means and having a power-enabling position and a power-disabling position, said limit switch being normally in power-enabling position, mechanical means controlled by said cam for operating said limit switch to power-disabling position when said rod is moved from its normal position to its stopping position, and a manually operable locking-type reset switch in said casing adapted for connection with said circuit means and having an inactive position and a power-enabling position, said reset switch being normally in inactive position and being manually operated to power-enabling position when said limit switch is in power-disabling position, and mechanical means controlled by said cam for restoring said reset switch to its normal position upon the return travel of said rod to its normal position.
